E. MINGE

SPARK PLUG

Filed Jan. 20, 1921

UNITED STATES PATENT OFFICE.

EINAR MINGE, OF CHICAGO, ILLINOIS.

SPARK PLUG.

Application filed January 20, 1921. Serial No. 438,565.

To all whom it may concern:

Be it known that I, EINAR MINGE, a former subject of the King of Norway (who has forsown his allegiance to said King of Norway and declared his intention of becoming a citizen of the United States), and a resident of the city of Chicago, county of Cook, and State of Illinois, have invented certain new and useful Improvements in Spark Plugs, of which the following is a specification.

My invention relates to new and useful improvements in spark plugs, and has for an object the provision of a combination spark plug and priming cup.

Another object is to prevent the formation of carbon in the spark plug;

And a further object is to admit air through the priming means to improve the gas mixture.

Other objects will appear hereinafter.

The invention consists in the combinations and arrangements of parts hereinafter described and claimed.

The invention will be best understood by reference to the accompanying drawings forming a part of this specification, and in which,

Fig. 1 is a vertical sectional view of a combination spark plug and priming cup, provided with an intensifier;

Fig. 2 is an inverted view, and

Fig. 3 is a plan view of the device shown in Fig. 1;

Fig. 4 is a vertical sectional view of another modified form of the invention; and

Figs. 5 and 6 are sectional views taken, respectively, on lines 7-7 and 8-8 of Fig. 4.

The form of invention illustrated in Figs. 1, 2 and 3 comprises a metal plug or sleeve 10 having a threaded end 11, adapting the device to be attached to the cylinder (not shown) of an automobile engine or similar combustion engine. A wire 12 is connected to the threaded end of the plug and contains a curved portion 13 at its center. Said plug embraces an insulating member 14, of porcelain or the like, carrying a sleeve 15 at its center and having a cup 16 formed at its upper end, in which is seated a metallic disk or screen 17 provided with perforations 18 and carrying a binding post 19 to which the terminal wire 20 is connected. A fibrous cup 21 is mounted above said disk 17 and a similar cup 22 mounted below the same with

their open ends joining, and a mica disk 23 is placed over perforations 24 provided in the top end of the upper cup. A stem 25 passes through a large central opening 26 in the metallic disk and through suitable openings in the mica disk and the ends of the cups 21 and 22. A valve head 28 is mounted on the lower end of said stem which seats in the valve seat 29 provided in the bottom of the sleeve 15, and a conducting wire 30 projects downward from said stem in close proximity with the wire 12, therewith forming the usual spark gap for the plug. A spring 31 surrounds the upper end of said stem bearing on the mica disk below and against a pair of lock nuts 32 above. Said nuts are adjustable on the stem to permit varying the tension in the spring and to thereby adjust the resistance of the valve and regulate the amount of air admitted through the valve on each suction stroke.

In this form of the invention the current passes from the wire 20 onto the metallic disk 17, jumps across the opening 26 to the stem 25, which forms the upper spark gap, continuing down said stem and wire 30 to the wire 12 at the lower end of the spark gap. The cup-shaped members 21 and 22 form a housing through the upper openings of which the upper spark gap may be viewed and to prevent any gas forming in the cup from entering the upper spark gap; and in view of the fact that the upper and lower spark gaps are connected in series, the firing of the upper gap would indicate that the lower gap is also firing and that the electric elements are functioning properly.

The form illustrated in Figs. 4, 5 and 6 comprises a screw threaded plug 50 embracing an insulating member 51 which carries a cup 52 at its upper portion and a sleeve 53 at its interior which is provided with a valve seat 54 co-operating with a valve head 55 mounted on a stem 56 provided at its lower end with a spark wire 57 which co-operates with a plate 58 formed at the middle portion of the conductor 59 attached to the lower end of said plug. A metal clip 60 is mounted on the upper edge or rim of the cup 52 and is provided with a binding post 61 to which is connected the terminal wire 62; from the clip 60 a wire 63 extends to the upper end of the stem 56 where it is held in position by a pair of adjusting nuts 64. A pair of disks 65 are mounted in a circular groove in said cup and are each pro-

vided with a pair of co-operating slots 66 and an engaging lug 67 on the upper one. Central openings 68 are provided in these disks for the passage of the stem 56 and a 5 spring 69 is mounted on the stem between the disk and the lock nuts, and by adjusting said nuts 64 the tension of the spring 69 may be varied to require a greater or smaller force of suction to open said valve 10 55, or even to retain said valve closed against said suction.

In this form of construction, by the use of the metal clip and the wire connecting same with the stem, the direct load is taken 15 off from the stem. The upper disk may be turned with respect to the lower one and the effective openings 66 varied to govern the amount of air to be admitted through the sleeve and to the firing gap existing between the wires 57 and the plate 58. The wire 57 is made of suitable length so that its lower end will impinge upon the plate 58 to remove the carbon therefrom upon the extreme downward motion of the stem during 20 each suction stroke of the cylinder piston, and may also be pushed down and turned on the plate to remove such carbon. This construction is effective in preventing the usual formation of carbon upon the contact member or spark element connected to the lower end of the spark plug.

It is thus evident that I have provided in both of these forms a combination spark plug and priming cup which may be used as 35 a priming cup by merely depressing the valve stem in the cup permitting gasoline or any similar fluid to pass to the spark gap, and have also provided a means which will permit air to be taken in to the device upon 40 each suction stroke, but remaining closed upon the three other strokes. This admission of air serves to break up the gas particles in the cylinder and improve the gas mixture, thus acting as a gas saver. The air 45 thus drawn through the spark plug into the cylinder upon each suction stroke of the piston of said cylinder prevents the formation of carbon at the lower end of the spark plug and at the spark gap.

50 While I have illustrated and described the preferred form of construction for carrying my invention into effect, this is capable of variation and modification without departing from the spirit of the invention. I, therefore, do not wish to be limited 55 to the precise details of the construction set forth, but desire to avail myself of such variations and modifications as come within the scope of the appended claims.

60 Having described my invention, what I claim as new and desire to secure by Letters Patent, is:

1. In a device of the class described, a spark plug provided with an insulating member bearing a cup at its upper end,

means movably mounted in said insulating member, said means having an electric terminal connected to its top, means for supporting said terminal on the wall of said cup, an electric terminal at the bottom of 70 said movable means, and means extending inward from the bottom of said plug forming a spark gap with said bottom terminal.

2. In a device of the class described a spark plug provided with an insulating member having an integral cup at its upper end, a perforated member mounted in said cup, a conductor movably mounted in said insulating member and passing through said 75 perforated member, said conductor having an electric terminal at its top and a terminal wire secured to its bottom engageable with a terminal on the bottom of said plug, a head on said conductor forming a valve in conjunction with the lower portion of 80 said insulating member, and spring means seated on said perforated member for normally retaining said valve closed and said bottom terminals separated.

3. A spark plug provided with an insulating member having a cup at its upper end, means mounted on the upper edge of said cup carrying the upper binding post, and an electric conductor leading from said binding post through said member and forming a spark gap at the lower end of 95 said plug.

4. A spark plug provided with an insulating member having a cup at its upper end, a clamping bracket mounted on the upper edge of said cup carrying the upper binding post, a member bridging the lower end of said plug, and an electric conductor between said binding post and said bridging member flexibly connected with said 100 post and forming a spark gap with said bridging member.

5. In a device of the class described a spark plug provided with an insulating member having an integral cup at its upper end, perforated disk means mounted in said cup, a conductor movably mounted in said insulating member and passing through said 110 perforated disk means, a terminal wire secured to the bottom of said conductor, a co-operating terminal member extending across the bottom of said plug, a member on said conductor forming a valve in conjunction with the lower portion of said insulating member, and spring means supported by 115 said perforated disk means for normally retaining said valve closed and said bottom terminals separated.

6. A spark plug provided with an insulating member having a priming cup at the upper end, means extending through said insulating member providing a fluid conduit from said cup to the lower end of said plug, a valve in said conduit, a spring to close said valve, and means mounted in said 125 130

cup to regulate the amount of fluid to be admitted to said conduit.

7. A spark plug provided with an insulating member having a priming cup formed integral with its upper end, a sleeve extending through said insulating member providing a fluid conduit from said cup to the lower end of said spark plug and a pair of cooperating perforated members mounted 5 in said cup to regulate the amount of fluid to be admitted to said conduit.
8. A spark plug attachable to an internal combustion engine and being provided with an insulating member having a priming cup 15 at its upper end, means extending through said insulating member providing a fluid
- conduit from said cup to the lower end of said spark plug, valve means mounted in said conduit and arranged to open automatically upon the suction stroke of the engine, 20 and a pair of relatively adjustable perforated discs mounted across an intermediate part of said cup to regulate the amount of fluid to be admitted to said conduit and valve. 25

In testimony whereof I have signed my name to this specification in the presence of two subscribing witnesses,

EINAR MINGE.
